LANTERN

Philip J. Mole, Elmwood Park, Ill.

Application September 12, 1958, Serial No. 52,624

Term of patent 14 years

(Cl. D48—24)

Figure 1 is an elevational view of a lantern, showing my new design;

Figure 2 is a top plan view;

Figure 3 is a bottom plan view thereof with the base removed for convenience of illustration;

Figure 4 is another elevational view as seen from one side; and

Figure 5 is a view taken on the line 5—5 of Figure 4.

The dominant features of my design reside in the portions shown in full lines.

I claim:

The ornamental design for a lantern, as shown and described.
